UNITED STATES PATENT OFFICE.

CHARLES C. CLARK, OF EAST ORANGE, NEW JERSEY.

HAIR-PIN.

973,404.

Specification of Letters Patent.

Patented Oct. 18, 1910.

Application filed November 16, 1909. Serial No. 528,322.

To all whom it may concern:

Be it known that I, CHARLES C. CLARK, a citizen of the United States, and a resident of East Orange, county of Essex, and State of New Jersey, have invented certain new and useful Improvements in Hair-Pins, of which the following is a full, clear, and exact description.

This invention relates more particularly to a hairpin which will lock itself in position when placed in the hair.

The primary object of the invention is to provide a simple and efficient hairpin in which a portion thereof is so formed that when pushed into the hair a part of the latter will be forced on opposite sides of its longitudinal center and through a space more or less confined to lock the pin in the hair; and to so construct the pin that by giving the same a relative movement, it will be substantially covered by the hair so that it cannot be easily lost and at the same time will prevent the hair from coming down by accident, but will permit the hair to be taken down when desired.

A further object of the invention is to provide a device which may be made of various kinds of material and in various forms to adapt it for the purpose intended.

With these and other objects in view, the invention will be hereinafter more particularly described with reference to the accompanying drawing, which forms a part of this specification, and will then be pointed out in the claim at the end of the description.

In the drawing, the figure represents an elevation of one form of hairpin embodying my invention.

The hairpin has a body portion 10 and a closed end or locking portion 11, and said body portion comprises two leg members 12 and 13 which are separated from each other and are adapted to be forced in the hair in the usual manner. The members 12 and 13 may be bent inward, as at 14, to provide a more or less confined space 15 for the hair to pass therethrough, and projecting outward on opposite sides of the longitudinal center of said device is a substantially U-shaped portion 16. This portion 16 forms a part of the closed end and together make a substantially heart-shaped portion integral with the body of the pin, and said por-

tions 16 meet at 17 in a curved part located substantially in alignment with the longitudinal center of the device. The portions 16 extend upwardly and outwardly beyond the legs of the pin and form a broad comparatively flat head therefor. It is important that this head be flat so that it will not project beyond the hair of the wearer and so that the pin will be invisible. It is also important that the pin head shall be broad in order that the hair retaining channel formed by the upper walls of the loops shall have ample capacity.

The hairpin may be made of any suitable material whether wire, celluloid, aluminum or any materials usually employed in the manufacture of such articles, and when using the said device the body portion 10 is forced in the hair in the usual manner, so that the hair will be forced into the parts 16 on opposite sides of the longitudinal center of the device to be held and confined therein. It will thus be seen that the loops 16 form broad, flat, shallow channels to receive the lock of hair that retains the pin in position. A part of the hair may be passed over the part 17 to be locked therein and by pushing one of the parts 16, as for example the end 18 of said part, so that the hair will cover the same, this will serve to further hold the device in the hair and prevent the same from being lost and also prevent the hair from coming down by accident.

From the foregoing it will be seen that simple and efficient means is provided whereby the said device will be locked in the hair; that said device overcomes the objections incident to hairpins as ordinarily constructed; that said device is simple in construction and may be cheaply made of various materials; and that said device is so constructed that it will permit the hair to be taken down without difficulty when it is desired to do so.

Having thus described my invention, I claim as new and desire to secure by Letters Patent:—

As an article of manufacture, a hair pin having leg members, loops extending upwardly and outwardly at the closed end of the pin at an oblique angle to the body of the pin, said loops projecting beyond the leg portions and forming a substantially

flat head to the pin, greater in width than the body of the pin, that portion of the pin forming the upper walls of the loops being connected together at a point directly over the center of the pin and being depressed or bent inwardly to form a hair-receiving channel at the top of the pin head.

This specification signed and witnessed this 5th day of November A. D. 1909.

CHARLES C. CLARK.
